UNITED STATES PATENT OFFICE

2,618,347

FIRE EXTINGUISHER

Gilmour C. MacDonald, Ames, Iowa

Application March 29, 1946, Serial No. 658,085

5 Claims. (Cl. 169—30)

1

This invention relates to fire extinguishing devices and more particularly to an improved means for producing atomization or fogging of fire extinguishing mediums and for projecting the same.

Present practice in producing water fog for fire fighting purposes employs a high pressure pump, usually engine driven from the fire truck, and apparatus which produces fog by the angular impingement of high pressure streams of water and by the action of suitable deflecting vanes or nozzles. Such a construction requires a relatively heavy high capacity driven pump together with high pressure hose, etc., for application.

It is an object of my invention to provide a compact and easily portable means for attaining the atomization of water or other fire extinguishing fluids with the further advantage of admixing with the projected fog entrapped gases which do not foster combustion, in contradistinction to the "fanning" effect often produced by conventional fog extinguishers due to a non-homogeneous fog projection and to the entrapment of air in the moving fog.

A further object of this invention is to provide means resulting in greater projection distance of the fire-extinguishing fog with a consequent increase in the utility and safety of the improved device.

My invention secures the object advantages stated above by employing gases generated from the combustion of a suitable propellant, usually a solid, to atomize and project a fog-like fire-extinguishing medium, as distinguished from present systems employing purely mechanical production of fog and from those systems employing a compressed gas, such as carbon dioxide, as the fog producing agent. It will be seen from the following description that my system for producing and projecting fog has many advantages, such as maximum portability in that power driven high-pressure pumps are not required, high safety in that it does not employ a separate or integral storage vessel for bottled gases under pressure, and excellent efficiency in that it provides for a maximum of gas generation in a minimum of storage space, thus insuring most fluid volume in a given size extinguisher. Other advantages of my fire extinguishing system are that the device does not have to be checked for gas pressure as is the case when compressed gases are used, the device may be easily serviced, in that additional prepared propellant cartridges may be inserted with no more difficulty than in reloading the conventional soda and acid type

2

fire extinguisher, and the device may provide a tremendous rate of discharge of fog if desired, by merely increasing the size of the propellant grain and fog-producing nozzle or play pipe.

5 This latter advantage is of special value in industrial and airport use where extremely high discharge rates are required for a relatively short time and where portability and ease of servicing are paramount in importance.

10 Other objects and advantages of the invention will be apparent during the course of the following description, reference being made to the attached drawing wherein:

15 Figure 1 is a vertical section view of the top portion of a small, portable fog fire extinguisher, intended for the same general usage as the common 2½ gallon "soda and acid" extinguisher now in extensive use.

20 Figure 2 is a vertical section view of my fog-producing device for application to a standard fire hose, whereby a fog producing nozzle is employed in place of the customary play pipe.

25 Referring to the drawings for the purpose of illustration, Figure 1 depicts a cross section through an extinguisher of the portable type shown prior to initiating operation. Ignition of the propellant grain 11, continued in the powder chamber 12 produces a rapid evolution of gases within the interior of cover 13. The propellant

30 grain may be any well known combustible material, such, for example, as rocket-type propellants composed of approximately equal amounts of nitrocellulose and nitroglycerin with small amounts of additives. One such propellant is described in United States Patent 1,923,849, issued to Stickland and Stevenson on August 22, 1933, and comprises fifty parts nitrocellulose, forty-one parts nitroglycerine, plus nine parts of diethyldiphenylurea and phenyl urethane. A propellant grain weighing of the order of one

35 pound is adequate to project the fog produced from two to five gallons of fire extinguishing medium. The gaseous products of combustion issue through the throat (narrowest portion) of

40 nozzle 14 at the local velocity of sound. 3,500 feet per second may be considered to be a representative throat velocity with modern solid propellants and this velocity may be greatly increased by expanding (as in supersonic wind tunnels) through the divergent portion of the nozzle.

45 This high speed gas jet siphons the water or other fire extinguishing medium up the annular passage 15, between the siphon tube 16 and the propellant chamber 12. The me-

chanical mixture of combustion gases and water or other fire extinguishing medium thus formed in the mixing zone of the nozzle 18 produces a finely divided fog which is projected out of the nozzle in the direction indicated by the arrow 19. The outer shell or reservoir of the extinguisher is indicated by the numeral 17, and a check or relief valve 20 permits the admission of air into the reservoir 17 as liquid is siphoned up the tube 16.

The ignition system whereby combustion of the propellant grain 11 is initiated may be either by electrical means as is current practice in the rocket art or may be by percussion, mechanically actuated, as is common practice in artillery and small arms constructions. For example, a conventional rocket propellant igniter is shown in Figures 1 and 2 in the form of a silk bag 33 containing a few grains of black powder and an electric squib connected to lead wires 34 extending out through the nozzles for connection to a conventional battery and switch.

A safety groove 21 may be employed to insure against generation of excessive pressures within the combustion chamber 12. Such a groove may be designed to fail at any desired pressure and upon separation will result in increasing the available gas exit area to such an extent that the propellant will then be extinguished. This construction is common practice in the rocket art.

Figure 2 depicts an installation intended for high rates of discharge and intended as a fog-producing adjunct to be coupled directly to fire hose lines. This may be considered as representative of either a "play pipe" which is attached to the delivery end of a fire hose and used to direct the discharge therefrom, or a branch supply pipe which forms part of a "fixed system." Ignition of propellant grain 22 by any of the several applicable means produces an evolution of gas inside the powder chamber 23 which is closed by the quick acting breech mechanism 24. The gases so generated are directed through the nozzle 25 and produce a rearward thrust sliding the nozzle assembly 26 rearward against stop 27, the nozzle assembly 26 being slidably secured to the inlet casting 28. This action opens the valve ports 32 between the inlet casting 28 and the nozzle assembly 26, permitting water from the fire hose, attached to threads 29, to flow through the inlet casting and into the area surrounding the powder chamber 23. The fog of water and gases thus produced in the mixing zone 30 issues from the nozzle in the direction shown by the arrow 31.

Not shown are the means employed for ignition of the powder grain, the handles for manually directing the nozzle or play pipe and the spring recoil mechanism whereby nozzle assembly 26 is returned to a position permitting no water flow when combustion of the propellant, with its attendant rearward reaction, ceases.

It will be understood that the scope of this invention is not limited to the exemplary structure illustrated and specifically described, but is limited only by the scope of the following claims.

I claim:

1. In a fire extinguisher for use with a hose supplying a liquid fire extinguishing medium, the combination comprising an inlet connection for said medium, a combustion chamber slidably carried by said inlet connection, a mixing cham-

ber carried by said combustion chamber, said mixing chamber having an outlet nozzle connected thereto, and valve means operable by sliding movement of said mixing chamber to an open position admitting the flow of said medium from said inlet connection into said mixing chamber.

2. In a fire extinguisher, the combination comprising a container for a fluid fire-extinguishing medium, a combustion chamber supported by said container and adapted to contain a combustible propellant, means for igniting a combustible propellant within said chamber, means defining an outlet nozzle connected to said chamber, and means defining a passage surrounding said outlet nozzle and communicating with said container for admitting said fluid fire-extinguishing medium into the combustion products emitted from said nozzle.

3. In a fire extinguisher, the combination comprising a container for a fluid fire-extinguishing medium, a combustion chamber supported by said container and adapted to contain a combustible propellant, means for igniting a combustible propellant within said chamber, means defining an outlet nozzle connected to said chamber, a second chamber surrounding said nozzle and communicating with said container for admitting said fluid fire-extinguishing medium into combustion products emitted from said nozzle, and means defining a second nozzle connected to said second chamber and coaxial with said first nozzle for directing a stream of mixed combustion products and fire-extinguishing medium.

4. In a fire extinguisher, the combination comprising, a container for a fluid fire-extinguishing medium, a combustion chamber supported by said container and adapted to contain a combustible propellant, an igniter for igniting a combustible propellant within said chamber, means defining an outlet nozzle connected to said chamber, means defining a chamber surrounding said nozzle, a siphon passage connecting said last chamber with said container, and an outlet nozzle for said last chamber for directing a stream of mixed combustion products and fire-extinguishing medium.

5. The method of producing a stream of fire-extinguishing fog which comprises the steps of igniting a combustible propellant within a chamber having an outlet nozzle, forming by said nozzle a high velocity stream of the gaseous products of the combustion of said propellant, and introducing said high velocity stream of combustion products a fluid fire-extinguishing medium, whereby said fire-extinguishing medium is drawn into and mixed with said combustion products to form a stream of fire-extinguishing fog.
